METHOD AND MEANS FOR HANDLING
TEXTILE FIBERS

Seymour S. Holt, Graham, N. C.

Application November 27, 1934, Serial No. 755,028

7 Claims. (Cl. 19—107)

This invention relates to a method and means of reclaiming stripings or waste from carding machines in cotton manufacture and also in the reclaiming and use of stripings from carding machines used for carding any type of textile fibers.

Heretofore, the conventional way of preparing textile fibers for a drawing operation has been to take the raw stock and put it into a bale breaker from whence it is carried to an opener and then to a Murray machine and the like. Then it is transferred from these machines by means of a main condenser onto an automatic picker feeder which feeds the raw stock to the pickers, usually first to a breaker picker which forms the fibers into laps and these lap rolls are placed into a finisher picker where the finished lap rolls are prepared. These finished lap rolls are then placed in the intake end of a carding machine from whence the fibers emerge in the form of a web and are drawn through a trumpet and deposited as a sliver into a suitable can. From the can, the slivers are fed to drawing machines, fly frames and the like, for the preparation of the finished yarn.

The carding machine has what is known as carding mechanism or carding cylinder with card clothing thereon and a doffer cylinder. The doffer cylinder has the web of textile fibers removed therefrom by a stripper comb or roll which strips it off in the form of a web which is condensed by means of a trumpet into a sliver. In the carding operation, the motes, leaves, dirt and other foreign substances are removed from the cotton or fibers. The carding cylinder has what is known as a stripper mechanism which strips the waste cotton onto a suitable roll where a roll of stripings is formed.

The rolls of stripings have heretofore constituted a source of great loss in the textile industry and especially in the manufacture of cotton goods. These stripings are filled with all kinds of impurities and heretofore have been of no value whatever except to be sold as waste. Some attempts have heretofore been made to take the stripings which run usually from three to six percent of raw stock and to throw them back into the opening machinery and rework them along with the raw stock. This has not been satisfactory on account of throwing a great quantity of dirt and foreign substance back into the raw stock thus resulting in imperfect cotton yarn being manufactured.

Furthermore, since the advent of the process-

ing tax on cotton, these stripings represent an investment of over four cents per pound plus the price paid for the cotton, which is much more than the stripings can be sold for in the open market as waste.

It is, therefore, an object of this invention to provide means whereby these stripings can be reconditioned and the foreign matter removed therefrom thus reclaiming the good cotton contained therein and working this good cotton in the conventional manner or depositing it in whatever percentage desired back into the working of the raw stock as the raw stock is prepared for the carding machines.

I accomplish this result by collecting the rolls of stripings and passing these rolls of stripings through conventional cleaning system, pickers, and carding machines, but instead of the carding machine taking the fibers therefrom in sliver form, the fibers are removed in loose form thus rendering the cotton into a state where it is easily mixed or handled as ordinary raw stock. If the fibers coming from the carding machines as a result of reworking the stripings, were saved in bulk in sliver form, it would be impossible to mix the stripings back into the opening machinery on account of the fact that the slivers or rolls would become entangled in the machinery; consequently, it would be impossible to work the same unless by hand operation, the slivers or rolls were torn into small bits which would be very expensive and the cost of such reworking would be prohibitive.

I therefore accomplish the desired result by providing certain of the carding machines with pneumatic suction nozzles located adjacent the stripping mechanism on the doffer cylinder of the carding machine which receives the loose cotton fibers from the doffer cylinder of the carding machine and conveys the loose cotton fibers thus reworked from the stripings back into the source of supply of the raw stock where I can mix it with other raw stock or work it separately as first grade cotton fibers.

Some of the objects of the invention having been stated, other objects will appear as the description proceeds, when taken in connection with the accompanying drawings, in which:—

Figure 1 is a diagrammatic lay-out of a textile plant equipped with my invention;

Figure 2 is a top plan view of the discharge end of a carding machine equipped with my invention;

Figure 3 is an elevation of the discharge end of

a carding machine equipped with my invention, showing the invention in elevation and the floor in section;

Figure 4 is a vertical sectional view taken along line 4-4 in Figure 3.

Referring more specifically to the drawings, the numeral 10 indicates a conventional bale breaker while 11 and 12 indicate other forms of openers which are connected in series by means of ducts 13, 14 and 15 to a suction pipe 16. The bale breakers and openers are usually located in one portion of the building or in a separate room from the rest of the machinery. The raw stock is placed into the bale breakers and passed therethrough and through the openers prior to its being fed to the pickers. The suction pipe 16 is connected to a main condenser and suction fan 17 from whence the raw stock is fed onto an automatic picker feeder 18 which feeds it to the breaker pickers 19 and 20, or as many additional pickers as may be deemed necessary.

The breaker pickers form the fibers into lap rolls and in more recent installations, finisher pickers or lappers are geared thereto and driven in unison therewith, there being several pickers in a row, and the fibers are fed continuously therethrough. In the present instance, the finisher pickers or lappers 21 and 22, are provided and the lap rolls are taken from the breaker pickers 19 and 20 and several of these lap rolls are usually placed in the finisher picker where they are all picked at the same time and formed into a finished lap roll at the discharge end thereof. These lap rolls are then taken to suitable carding machines 30 and fed to the intake end thereof. These lap rolls are carded and the cotton emerges from the discharge end of the carding machine, said cotton being discharged from the doffer cylinder by a stripper comb or roll into the form of a very fine web. This web is usually passed through a trumpet where it is condensed and passed through a coiling mechanism where the slivers, which are condensed in the trumpet, are deposited in suitable containers. These containers are then placed at the intake end of the drawing machinery for successive operations for drawing, spinning and twisting the fibers into a finished yarn.

The carding machines also have stripper rolls which collect the stripings from the carding machines. These stripings are waste cotton, leaves, husks, dirt, and in fact all of the impurities in the cotton are collected on the stripper rolls. Heretofore, these stripings have been sold as waste and in a few instances, as heretofore stated, have been thrown back into the opening room where they are mixed with the raw stock but this means that all of these foreign substances which compose a great percentage of the stripings, are thrown into the pure raw stock which contaminates the same and results in inferior slivers, resulting in inferior yarn.

I have provided a method and means whereby these stripings can be reworked and thus a great saving is effected. The cotton laps normally produced on machines 21 and 22 are not carded on machines 25 to 27, but are carded on the conventional carding machines having coiler and trumpet mechanisms. I provide one or more of the carding machines 25, 26 and 27 in my establishment with a different form of mechanism for receiving the fibers from the discharge end thereof. Instead of withdrawing the web from the doffer cylinder in the form of a sliver, I prefer to doff it in a form of loose cotton. These special carding machines 25, 26 and 27, therefore have

the trumpet and coiling mechanism removed and in lieu thereof I secure nozzles 30, all of the nozzles being identical, on one or more of the carding machines which I may use for these lap rolls of stripings. The stripings are collected from day to day and I then take these stripings and pass them through the opening and cleaning machines and the pickers to form lap rolls and then feed them to the intake end of the special carding machines having the suction nozzles 30 and record 10 these stripings to remove therefrom the impurities. If desired, I could take them out of the carding machine in sliver form, but this would not be as finished a product as from the raw stock as there might be a slightly higher percentage of 15 impurities in this reworked stripping stock than in the raw stock. I therefore deem it better, on account of the fibers being probably somewhat shorter in the stripings than in the raw stock, to mix these recorded stripings back into the raw 20 stock.

For carding the lap rolls of stripings the coiler mechanism, the trumpet and rolls are removed from the carding machines 25, 26 and 27 and the nozzles 30 are secured thereto disposed in close 25 proximity to the doffer cylinder 31 of the carding machine. The stripper comb 32 is conventional and it is oscillated by means of an oscillating shaft 33 which is a conventional structure and the web 34 of the recorded stripping, instead of being 30 formed into a sliver by the trumpet and coiling mechanism, is received into the upper end of the nozzle 30. Each one of the nozzles 30 has a duct 36 secured at the lower end thereof which is connected to a main duct 37. The main duct 37 35 is usually disposed beneath the floor 37a of the mill in which the carding machines are located, although it is evident that it could all be handled on one floor of the mill. The main duct 37 passes into another room and is forked, forming portions 38 and 39 with gates 40 and 41 respectively, therein. The branch 38 is connected to the intake end of combined suction fan and condenser 42 whose discharge pipe 43 usually leads to an exhaust flue 44 on the exterior of the mill. This 45 condenser and fan 42 is usually disposed immediately above a self-feeding hopper 45 and the recorded stripings are allowed to drop from condenser 42 into the self-feeding hopper 45 in case the opening machinery, pickers and the main condenser and fan 17, previously described, are not in operation. This means that the carding machines 25, 26 and 27 may be operated for the reworking of the stripings while the rest of the machinery is not in operation if desired, and the 55 stripings which are being reworked are withdrawn from the carding machines 25, 26 and 27 by means of the suction nozzles 30 and deposited in the self-feeding hopper. Later on, when the pickers are started in operation as well as the 60 drawing in of additional raw stock from the opening room, the self-feeding hopper can be set into operation to feed the rejuvenated stripings at whatever rate desired to cause them to be withdrawn by a suction tube 48 which is connected to 65 the lower portion of the self-feeding hopper. These rejuvenated stripings are passed through tube 48 into tube 49 and to main condenser and fan 17. When this is being done, of course gate 41 will be closed.

However, if the recorded stripings should be desired to be fed at full rate into the main condenser and fan 17 along with raw stock which is being opened up in the opening room and drawn into the main condenser through duct 16 by the 75

suction fan therein, then gate 40 will be closed and gate 41 will be opened and the webs drawn by suction from the carding machines through the nozzles 30 will be fed directly through the 5 pipe 39 into pipe 49 and into the main condenser in a greater proportion with the raw stock coming from the opening room.

Also if desired, the opening room could be put out of operation and the recarded stripings 10 could be drawn through tube 39 into the main condenser and could again be drawn through the breaker and finisher pickers to form lap rolls for the conventional carding machines to be again carded and passed into sliver form into the coiling 15 mechanism for the draft machinery.

While I have shown the web of fibers being removed from the discharge end of the carding machine by suction, it is evident that other suitable 20 means can be employed for removing these fibers in loose form from the carding machine.

In the drawings and specification there has been set forth a preferred embodiment of the invention, and although specific terms are employed, they are used in a generic and descriptive 25 sense only, and not for purposes of limitation, the scope of the invention being set forth in the appended claims.

I claim:

1. That method of re-working stripings from 30 carding machines for textile fibers which comprises collecting the stripings and cleaning the same to form the stripings into lap rolls and then recarding the stripings and removing the web of recarded stripings from the carding machine 35 in the form of a loose web.

2. That method of reclaiming the textile fibers in stripings in carding machines which comprises collecting the stripings and forming the same into lap rolls and then carding the stripings, then removing the carded stripings from 40 the carding machines in loose form and then mixing the loose stripings with raw stock to utilize the stripings in the manufacture of yarn.

3. Apparatus for handling stripings taken 45 from carding machines having a doffer cylinder which comprises a suction nozzle associated with the doffer cylinder of a carding machine for receiving the fibers doffed from the doffer cylinder, a suction pipe connected to the nozzle, a condenser comprising the usual separator and suction fan associated with the suction pipe for moving the fibers through the nozzle and suction pipe

and means connected to said condenser for withdrawing fibers from another source to mix the same with the stripings removed from the carding machine.

4. Apparatus for handling textile fibers comprising a carding machine, a nozzle disposed in close proximity to the discharge end of the carding machine, a condenser, a suction pipe connected to the nozzle and to the condenser for conveying fibers from the carding machine to the 10 condenser, a container disposed beneath the condenser and into which the fibers conveyed to the condenser may fall, a second condenser, means for feeding raw stock of textile fibers to the second condenser, means for conveying textile fibers 15 from the container to the second condenser whereby the two types of textile fibers are intermixed.

5. Apparatus for handling textile fibers from a carding machine comprising means for stripping the fibers from the machine, a suction nozzle associated with the discharge end of the carding machine for conveying the web therefrom in loose form, and a suction condenser connected to said 20 nozzle.

25 6. A carding machine having a doffer cylinder and a stripper knife, a nozzle disposed in close proximity to the stripper knife and the doffer cylinder and suction means connected to the nozzle for drawing the web discharged from the 30 doffer cylinder into the nozzle.

7. Apparatus for handling textile fibers comprising a bale breaker, an opening machine, a condenser, a suction pipe connecting the bale breaker and the opener to the condenser, a picker, means for feeding the fibers from the condenser to the picker, a self-feeding hopper, a suction pipe connecting the condenser and the self-feeding hopper, a carding machine, a nozzle disposed at the discharge end of the carding machine 35 for receiving the web therefrom, a second condenser disposed above the self-feeding hopper, a piped connection between the nozzle and the second condenser, a second piped connection between the first piped connection and the first 40 condenser, a third piped connection between the self-feeding hopper and the first condenser, and gates in the first and second connections for selectively directing the fibers from the carding machine to the first or second condenser. 50

SEYMOUR S. HOLT.
